Sylvester S. Savage,

BY Drake & Co. ATTY'S.

UNITED STATES PATENT OFFICE.

SYLVESTER S. SAVAGE, OF HARRISON, NEW JERSEY.

APPARATUS FOR PRESERVING FRUITS.

SPECIFICATION forming part of Letters Patent No. 531,067, dated December 18, 1894.

Application filed March 20, 1894. Serial No. 504,415. (No model.)

To all whom it may concern:

Be it known that I, SYLVESTER S. SAVAGE, a citizen of the United States, residing at Harrison, in the county of Hudson and State 5 of New Jersey, have invented certain new and useful Improvements in Apparatus for Preserving Fruits; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to overcome certain objections inherent in the devices heretofore employed for preserving fruits, to facilitate the operation, and to lessen or prevent the danger of scalding the hands during 20 the operation.

The invention consists in the improved apparatus and in the arrangements and combinations of the parts thereof, as herein set forth, and finally pointed out in the claim.

25 Referring to the accompanying drawings in which similar letters of reference indicate corresponding parts in each of the figures where they occur, Figure 1 represents a central longitudinal section of my improvement, and an 30 ordinary wash-boiler broken off at the top, in which the said apparatus is contained, a series of jars being shown in elevation therein. Fig. 2 is a top plan view of the apparatus apart from the boiler, and Fig. 3 is an elevation of the same.

35 In said drawings A and B, designate the top and bottom plates, respectively, of a holder or receptacle for the jars; said top plate being provided with a series of openings, a, 40 corresponding in size with the ordinary preserve jars, and the bottom plate being perforated as indicated in Fig. 2. The edges of the top and bottom plates are returned and inclose a stiffening wire, a', to make the 45 edges round so as to prevent any abrasion of the hands in handling the same. The top and bottom plates are held apart the required distance by means of vertical plates C, which are secured thereto by solder or otherwise,

50 as indicated in Figs. 1 and 2. At about the center of the holder is a handle, D, which is formed by bending a piece of metal, substan-

tially elliptical in cross-section and having the ends extended from the lower side and inserted through the top plate down to the 55 bottom plate, and securely fastened to both by means of solder or otherwise, so as to hold the two rigidly in position and relieve them from undue strain in the act of lifting the holder when filled with cans or jars of fruit. 60 The longer portion of the handle is located lengthwise of the holder so that if there are more jars in one end of the holder than the other the handle can be grasped nearer one end than the other and thereby prevent the 65 holder from tipping; and by bringing the ends of the handle toward each other they can be passed down through the plate without coming in contact with the jars, which would be the case if they were bent downwardly directly from the ends of the bend, 70 as will be evident from an inspection of Fig. 2. The bottom plate is also provided with five feet, b, one at each corner, and one in the center, to keep the holder from coming into 75 contact with the bottom of the boiler, and to permit a free circulation beneath and through said bottom. The edges of said handle are also returned and inclose wires to stiffen the same and prevent abrasion of the hands in 80 the handling.

By means of this device, all danger of burning or scalding the hands while inserting or removing the fruit jars from the boiling water is avoided, as the said jars are seated in 85 the holder before they are placed in the hot water. Moreover the handle being in the center and extending considerably above the top of the holder may, with the cans inserted be set in the water before it is heated or while 90 warm and be lifted therefrom without danger of scalding; and the same is true when removing the cans from the boiling water. Instead of being forced to put the hands down into the boiler and very close to the boiling 95 water, in order to seize the jars or cans, the holder is simply seized by the handle and lifted out of the boiler together with the jars therein without any danger of being burned, as the hand is some distance removed from 100 the boiling water.

The apparatus is made entirely of tin, but may be made of any suitable metal, such as brass, zinc or other metal, and being made in

form to correspond with an ordinary wash-boiler, the latter may be utilized in the operation of preserving the fruit, the only requisite being that the boiler should be a little larger 5 all around than the holder so as to permit its free removal therefrom.

The mode of operation is as follows:—Place the fruit, sugar, water and other necessary ingredients in the jars, then place the jars 10 with covers secured loosely thereon in the holder, then lift the latter by the handle, and place it in the boiler which must have sufficient water in it to cover the jars up to the neck, then place the boiler on the stove and 15 let the water come to a boil, after which fifteen or thirty minutes will suffice to cook any ordinary fruit. When the latter has been sufficiently cooked, the holder with its contents, is simply removed by taking hold of 20 the handle and lifting it out of the boiler, when the jars may be readily removed without any danger of scalding the hands. Thus the fruit will not be marred or mashed in any 25 way, as it would be by cooking it in the ordinary manner, as no undue handling is required; neither will it lose any of its flavor.

Having thus described my invention, what I claim as new, and wish to secure by Letters Patent, is—

The improved holder or receptacle for fruit jars, in which is combined a top plate having a series of openings therein to receive the fruit jars, a bottom plate on which said jars rest and having a supporting foot at each corner, a series of side plates securing said top and bottom plates in position, and a lifter composed of a single piece of sheet metal bent to form a handle at the apex or top, and two prongs arranged parallel with each other which pass through the central portion of 40 said top plate to the bottom plate and securely fastened to each to hold them in position, and a central support or foot, secured to said bottom plate, as described and for the purposes set forth.

In testimony that I claim the foregoing I have hereunto set my hand this 10th day of March, 1894.

SYLVESTER S. SAVAGE.
